UNITED STATES PATENT OFFICE.

THOMAS JOHN CHAPPELL, OF COGSWELL, NORTH DAKOTA.

TOOL-CASE FOR AUTOMOBILES.

1,237,750.

Specification of Letters Patent. Patented Aug. 21, 1917.

Application filed May 3, 1916. Serial No. 95,141.

To all whom it may concern:

Be it known that I, THOMAS JOHN CHAPPELL, a citizen of the United States, residing at Cogswell, in the county of Sargent and State of North Dakota, have invented certain new and useful Improvements in Tool-Cases for Automobiles; and I do hereby declare the following to be a full, clear, and exact description of the invention, such as will enable others skilled in the art to which it appertains to make and use the same.

The invention relates to improvements in tool cases for automobiles.

The object of the present invention is to improve the construction of tool cases for automobiles and to provide a simple, practical and inexpensive tool case designed particularly for use on Ford automobiles and adapted to be arranged beneath the front seat in rear of the legs of the driver or operator in the space unoccupied at present and adapted to be readily opened and closed and capable when open of arranging the tools upon the floor of the car within easy access at the door of the same and adapted when closed to prevent the tools from rattling or becoming lost.

A further object of the invention is to provide a tool case of this character equipped with a fabric tool bag adapted to receive tools of different sizes and capable of maintaining the same separate, clean and without any chance to rattle and also adapted to extend the outer or exposed portions of the tools in the same general direction so as to be within easy reach and to facilitate their ready removal by a person standing at the open door of a machine.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings

Figure 1 is a perspective view of a tool case constructed in accordance with this in-

vention and shown applied to a Ford automobile,

Fig. 2 is a vertical sectional view of the same,

Fig. 3 is a horizontal sectional view, the tool case being open.

Fig. 4 is an enlarged vertical sectional view of the tool case, the door being partially open.

Like numerals of reference designate corresponding parts in the several figures of the drawings.

In the accompanying drawings in which is illustrated the preferred embodiment of the invention the tool case which is designed particularly for use on Ford automobiles, may of course be applied to various other types of cars and it comprises in its construction a casing 1 constructed of galvanized sheet metal or other suitable material and designed to be painted or otherwise finished and located beneath the front seat 2 in a vertical position and provided at opposite sides with wings or extensions 3 arranged in flush relation with the front edges of the casing and extending to the sides of the body 4 of the car so as to present a smooth exterior and at the same time support the casing in an upright position. The vertical casing which may be rigidly secured to the automobile by any suitable fastening devices and which is shallow is composed of a back, and narrow top, bottom and side walls 5, 6, and 7 and the extensions or wings 3 are connected with the side walls and are provided at their outer edges with flanges 8. The sides or wings may be secured to the car in any desired manner and they extend from the top wall to the bottom wall of the shallow vertical casing, such as screws 8a.

The casing is equipped with a door 9 having top and side flanges 10 and 11 and hinged to the casing at the bottom thereof by a transverse rod 12, the side flanges 11 being cut away at 13 at the bottom to clear the pintle rod 12. The top and side flanges of the door 9 are narrow to correspond with the walls of the vertical casing and they fit within the same. The side flanges 11 are equipped with suitable catches 14 adapted to engage openings 15 in the side walls of

the casing. The catches yieldably engage the casing and may be of any desired construction and enable the door to be opened and closed by a handle 16. The catches 5 may be of any desired construction as the specific construction thereof does not constitute a portion of the present invention further illustration and description thereof is deemed unnecessary.

10 The door which is hinged at the bottom of the automobile is adapted to be opened out upon the floor of the same as illustrated in dotted lines in Fig. 1 of the drawings and as shown in full lines in Fig. 3 is equipped 15 with a tool bag 17 constructed of canvas or other suitable fabric and extending the entire length of the inner or lower portion of the door and having an angularly disposed upper or outer edge 18 from which extend 20 angularly disposed pockets 19 adapted to receive tools and extending in the same general direction toward the outer corner of the door so as to be within easy reach of a person at the side of the automobile with 25 the door open. By this arrangement the tools may be readily removed from the tool bag and easily replaced therein. The separate pockets maintain the tools separated and prevents the same from becoming lost 30 or rattling.

It will be seen that the tool case is exceedingly simple and inexpensive in construction, that it is adapted to be readily applied to a Ford or other automobile and 35 that it occupies a relatively small amount of space and is out of the way and at the same time is capable of enabling an entire set of tools to be quickly arranged in a convenient position for instant use.

40 What is claimed is:—

1. A tool case of the class described including a shallow upright casing designed to be arranged beneath the front portion of the seat of an automobile and provided with 45 means for rigidly securing it to the latter, a door hinged at the bottom to the casing

and arranged to swing downward and be supported upon the floor of the automobile and means located at the inner face of the door for holding tools whereby the latter 50 will be arranged upon the floor of the automobile when the casing is open and will be housed within the casing when the door is closed.

2. A tool case for automobiles including 55 a shallow upright casing designed to be arranged beneath the front portion of the seat of an automobile and provided at opposite sides with laterally projecting wings rigid with the casing and extending to the sides 60 of the body of the automobile and arranged in substantially flush relation with the exterior surfaces of the casing and a door hinged to the casing at the bottom thereof and arranged to swing downwardly to rest 65 upon the bottom or floor of the car when open.

3. A tool case of the class described including an upright shallow casing composed of top, bottom, and side walls and provided 70 with lateral extensions having flanges at their outer ends and a door hinged at the bottom to the casing and arranged to swing downwardly upon the bottom or floor of the body of an automobile. 75

4. A tool case of the class described including a shallow upright casing designed to be arranged beneath the front portion of the seat of an automobile, a door hinged at the bottom to the casing and arranged to 80 swing downwardly upon the floor of the automobile and a tool bag carried by the door and provided with an inclined edge and having angularly disposed pockets extending toward the upper or outer corner of 85 the door.

In testimony whereof I affix my signature in presence of two witnesses.

THOMAS JOHN CHAPPELL.
